UNITED STATES PATENT OFFICE.

IDA NORA IKER, OF CLAYTON, NEW MEXICO.

BROOM-HOLDER.

1,285,195.

Specification of Letters Patent. Patented Nov. 19, 1918.

Application filed January 19, 1917. Serial No. 143,259.

To all whom it may concern:

Be it known that I, IDA NORA IKER, a citizen of the United States, residing at Clayton, in the county of Union and State 5 of New Mexico, have invented certain new and useful Improvements in Broom-Holders; and I do hereby declare the following to be a full, clear, and exact description of the invention, such as will enable others 10 skilled in the art to which it appertains to make and use the same.

This invention relates to improvements in broom holders.

The object of this invention is the provision 15 of a broom holder which is especially adapted for the replacing of the broom straws therein at the will of the user.

A still further object of this invention is the provision of a broom holder which is especially 20 adapted for holding broom straws for making brooms or the like and is so equipped that the broom straws may be removed when they become worn and replaced by new broom straws thus furnishing a 25 new broom.

A still further object of this invention is the provision of a broom holder which is especially 30 adapted and equipped with novel means for holding the broom straws rigidly in position thus preventing loose straws from being scattered about during the sweeping action or using of the broom.

A still further object of this invention is the provision of a holder which is especially 35 equipped with novel means whereby the broom straw may be easily and quickly removed therefrom and replaced at the will of the user, and with a comparatively small amount of labor.

40 A still further object of this invention is the provision of a broom holder which is simple, practical, and comparatively inexpensive in construction, and one that can be manufactured and sold at a low cost.

45 With these and other objects in view the invention consists in the novel combination and arrangement of parts hereinafter more fully described and set forth in the claims hereto appended.

50 In the drawings:

Figure 1 is a vertical sectional view taken through my improved broom holder as made in accordance with this invention.

Fig. 2 is a sectional view taken on the line 2—2 of Fig. 1.

55

Fig. 3 is a side elevation illustrating my improved holder in its assembled position.

Fig. 4 is a front elevation.

Like numerals of reference designate corresponding parts in all the figures of the 60 drawing.

Referring more particularly to the drawings, the numeral 1 designates my improved broom holder in its entirety and it is constructed of metal or aluminum or any other 65 material suitable for the purpose. The holder comprises in its construction a rectangular body which has a rear wall 2, a front wall 3, which front wall constitutes a hinged lid which will be hereinafter more 70 fully described. The front and rear walls 2 and 3 which are connected by an end wall 4, and the upper ends of the front, rear, and end walls are tapered upwardly as at 5 and terminate into a cylindrical handle 75 receiving sleeve 6 in which is rigidly secured a handle 7 by suitable rivets 8.

The front wall 3 is hingedly secured as at 9 so as to permit access to the interior of the rectangular body 1. A coil spring 10 80 is arranged horizontally within the rectangular body 1 at a point above the hinged connection of the cover therewith. The opposite ends of the coil spring 10 are extended as at 11 in opposite directions and 85 have their free terminals terminating into attaching portions or members 12. One of the attaching portions of one end of the spring 10 is rigidly secured as at 13 to the rear wall of the holder 1, while the opposite attaching member 12 of the spring 10 is detachably connected to the cover 3 as at 14, the angularly bent end 12 extending into an eye 15 which is carried on the inner face of the cover adjacent its hinged connection. 90 A reinforcing rod 16 is arranged horizontally through the coils of the spring 10 and has its ends extending rearwardly as at 17 and extended through eyes 18 which are secured to the inner side of the rear wall 2 100 of the holder 1. The extreme ends of the wire 17 are secured to the inner side of the front wall 3 as at 14' of the holder 1 above the hinged portion thereof thus rigidly supporting the spring in position within the 105 body of the holder 1.

The eye 15 which is secured to the lid 3 permits the spring to be disconnected from the front portion so that the same may be raised and access to the interior of the body 1 obtained.

A plurality of clamps 20 are arranged in pairs and one clamp of each pair is secured to the inner face of the rear wall 2, and the other clamp of the pair is secured to the inner face of the cover 3 and their body portions being in direct alinement with each other so as to effectively bind against the opposite sides of the upper ends of broom straw 21 when between the rear wall and front wall of the holder 1 thus effectively holding the broom straws against movement when positioned in the holder 1. A second pair of clamps 22 are secured to the inner face of the rear wall 2 and front cover 3. The members 22 are located adjacent the lower edges of the rear wall and the front wall 3 as clearly shown in Fig. 1 of the drawings. The front face of each of the members 22 are provided with teeth 23 which bite into the broom corn and effectively hold the same positioned between moving cover 3 and the rear wall 2 of the holder 1. The broom straw 21 is arranged between the end walls 4 and the front and rear walls 3 and 2 of the holder 1. By positioning the clamping members 20 adjacent the hinged or upper end of the holder and arranging the clamping members 22 adjacent the lower edges thereof, the broom straw 21 has its upper ends effectively secured within the holder 1 when the device is in use. The detachable end of the spring 10 or its connection with the eye 15 carried by the cover 3 prevents movement upwardly of the cover 3, and to further hold the cover 3 against outward movement there is provided a hook 24 which is pivotally secured as at 25 to the exterior of the end wall 4 and has its hooked end 26 detachably engaging an eye or detachably holding the cover against outward swinging movement with relation to the rear wall 2 of the holder 1.

When it is desired to remove the broom straw 21 and replace the same with new

material, it is only necessary to detach the hooks 24 from their respective eyes 27 located on the cover 3 and by grasping the lower edge of the cover with one hand and lifting upwardly, the opposite hand may be slipped between the cover and release one end of the spring 10 out of the eye 15 and the cover may be readily kept open until the new broom straw 21 is placed in proper position.

What is claimed is:

1. A broom holder of the class described including a body, said body having its front wall hinged and constituting a cover, broom straws positioned between the front and rear walls of the cover, clamps carried by the rear wall and the hinged cover for engaging the straws, spring means arranged in the body and engaging the cover for normally holding the same in its closed position and the clamps in engagement with the straws, and means carried by the hinged wall and detachably engaging the rear wall to positively hold the cover in its closed position.

2. A broom holder of the class described including a body, said body having its front wall hinged and constituting a cover, broom straws arranged between the rear wall and the cover, clamps carried by the rear wall and the hinged cover for engaging the broom straws, a coil spring arranged in the body, having one end thereof rigidly secured to the rear wall of the body, and its opposite end detachably secured to the hinged cover for normally holding the cover in its closed position in engagement with the straws, the end of the spring engaging the cover being detachable therefrom so that the spring can be detached and the cover held in its raised position, and hooks carried by the hinged cover for engaging the body to positively hold the cover in its closed position.

In testimony whereof I affix my signature in presence of two witnesses.

IDA NORA IKER.
